(No Model.)

R. STEEL.
Sewing Machine Treadle.

No. 234,498.

Patented Nov. 16, 1880.

UNITED STATES PATENT OFFICE.

ROBERT STEEL, OF PHILADELPHIA, PENNSYLVANIA, ASSIGNOR OF FOUR-FIFTHS OF HIS RIGHT TO CHARLES H. BINNS, ADAM STEINMETZ, JR., CHARLES A. SPRING, AND WM. A. NICHOLS, OF SAME PLACE.

SEWING-MACHINE TREADLE.

SPECIFICATION forming part of Letters Patent No. 234,498, dated November 16, 1880.

Application filed September 28, 1880. (No model.)

To all whom it may concern:

Be it known that I, ROBERT STEEL, a citizen of the United States, residing at Philadelphia, in the county of Philadelphia and State of Pennsylvania, have invented a new and useful Improvement in Sewing-Machine Treadles, of which the following is a specification.

The nature of my invention mainly consists in the combination of a coil-spring with the upper end of the treadle of a sewing-machine and the table in such a manner as to assist in returning the treadle from its backward to its forward position, and also to hold it securely in the latter position when the machine is not in motion, as hereinafter fully described.

In the accompanying drawings, which make a part of this specification, Figure 1 is a front view of my improved treadle in connection with the table of a sewing-machine. Fig. 2 is an edge view of the same. Fig. 3 is a vertical longitudinal section, on an enlarged scale, of the bracket C, barrel D, pin a, and the upper part of the coil-spring E. Fig. 4 is a cross-section taken at the dotted line x x of Fig. 3. Fig. 5 is a cross-section taken at the dotted line y y of Fig. 3 on double the scale thereof, showing the spring E in connection with the barrel D and treadle B and the barrel in connection with the pin a by means of the spline d and groove e. Figs. 6 and 7 are respectively end and side views of the barrel D on an enlarged scale, showing a modified form of means for adjusting the barrel by the ratchet-wheel G and pawl i. Fig. 8 is another modified form, in which the bracket C and barrel D are in a single piece.

Like letters of reference in all the figures indicate the same parts.

A represents the table of a sewing-machine, and B an oscillating treadle, connected therewith by means of the bracket C and center-pin a. The treadle is provided with two arms, b and b', at its upper end. The arm b connects with the lug c of the bracket, which also has lugs c', c², and c³ for the support of the center-pin a, on which the arm b' oscillates, the arms fitting between the lugs c² and c³.

D is a barrel on the center-pin a, and E a spring, one end of which is attached to the barrel and coiled around it. The other end is fastened to the upper end of the treadle B, as represented in the drawings, to assist in returning the treadle in each revolution of the crank to its front position, and also to retain it in that position when the machine is not at work.

To provide for a quick and accurate adjustment of the tension of the spring, the center-pin a has a screw-connection with the lug or projection c' of the bracket C, as shown in Fig. 3, so that by placing a wrench on the head g of the pin and turning the pin in the right direction the proper axial adjustment of the barrel may be effected. The pin a is provided with a spline, d, which connects with the longitudinal groove e in the eye of the barrel, and is adapted to slide therein to avoid the longitudinal movement of the latter during the like movement of the pin in the axial adjustment of the barrel in regulating the tension of the spring, and thus admitting of the barrel fitting snugly between the lugs c' and c² to keep the spring in line with the vertical plane of the movement of the treadle. The lug c' has a groove, e', somewhat larger than the spline d, for the passage of the latter in connecting the pin a with the lugs c', c², and c³. The pin is held securely in its adjusted position by means of the jam-nut f.

Figs. 6 and 7 show a modification of the construction, whereby the axial adjustment of the barrel D is effected. The latter is provided with a ratchet-wheel, G, on one end, with which the pawl h engages when the barrel is turned in the proper direction by means of a wrench placed at i, where the barrel is the proper form to fit the wrench. The pawl is hung on the pin j, which is screwed into the lug c' of the bracket C. The barrel turns freely on the pin a, the latter being fastened in the lugs c', c², and c³.

If desired, instead of the barrel D having an axial movement, it may have a fixed position between the lugs c' and c² and form a part of the bracket or casting C, as shown in the

large vertical longitudinal section, Fig. 8; and instead of the bracket being in a single piece, I may sometimes make it in sections.

A spiral spring placed on the barrel D or 5 pin *a* may take the place of the coil-spring E. The latter, however, is preferable, being more durable, as the strain is in the direction of the longitudinal position of the fibers, while there is much lateral strain on the fibers of spiral 10 springs.

I claim as my invention—

1. The combination, with the table A, of the bracket C, the treadle B, pivoted to said bracket, pin *a*, barrel D, and spring E, connected at its 15 ends to said barrel and treadle, substantially as described.

2. The combination, with the table A, of the bracket C, treadle B, pivoted to said bracket,

pin *a*, barrel D, spring E, connected at its ends to said bracket and treadle, and means whereby said barrel may be turned and secured in any desired position for the purpose of adjusting the stress of the spring E, substantially as described. 20

3. The combination, with the bracket C, having lugs *c' c² c³*, of the treadle B, pin *a*, having a spline, *d*, barrel D, having groove *e*, spring E, connected at its ends to said barrel and treadle, and means whereby said barrel may be turned and secured, substantially as 25 30 described.

ROBERT STEEL.
